UNITED STATES PATENT OFFICE.

ROBERT H. WARREN, OF WASHINGTON, DISTRICT OF COLUMBIA.

SECURING DEVICE FOR STAIR-RODS.

SPECIFICATION forming part of Letters Patent No. 744,949, dated November 24, 1903.

Application filed June 22, 1903. Serial No. 162,670. (No model.)

To all whom it may concern:

Be it known that I, ROBERT H. WARREN, a citizen of the United States, residing at Washington, in the District of Columbia, have invented certain new and useful Improvements in Securing Devices for Stair-rods; and I do hereby declare the following to be a full, clear, and exact description of the invention, such as will enable others skilled in the art to 15 which it appertains to make and use the same.

My invention relates to a securing device or anchoring attachment for stair-rods; and it consists of certain novel features of combination and construction of parts, the preferred form whereof will be hereinafter clearly 15 set forth, and pointed out in the claims.

The prime object of my invention, among others, is to provide simple, cheap, though reliably-efficient means for securing a stair-rod in its adjusted position within the angle formed by the tread and risers of a stairway, whereby the rod will be firmly and securely disposed in its operative position, though easily and quickly removed therefrom when 25 it becomes desirable to take up the carpet for the purpose of cleansing or replacing the same.

Other objects and advantages will be hereinafter fully specified, reference being had to 30 the accompanying drawings, which are made a part of this application, and in which—

Figure 1 shows a portion of a stairway, illustrating the preferred means of holding the stair-rods in position. Fig. 2 is a perspective detail view of the ornamental securing device for holding the stair-rod in place. Fig. 3 shows a central section of the end of a stair-rod and my securing device, each of said 35 parts being illustrated in their respective operative places. Fig. 4 is a perspective detail view of my securing device, wherein a slightly-varied form of construction is employed. Figs. 5, 6, 7, 8, and 9 show other forms of construction or materialization of the same 40 idea embodied in my securing device.

In order to conveniently refer to the various elements of my invention and co-operating accessories, numerals will be employed, the same numeral applying to a similar part 45 throughout the several views.

Referring to the numerals on the drawings, 1 and 2 designate, respectively, the treads

and risers of a stairway of the usual or any preferred construction, while 3 indicates a stair-rod formed substantially in the usual 55 manner as a quarter-round of any suitable material, each of which is provided in the end sections thereof with a suitable opening or recess 4, while the numeral 5 designates an ordinary eye-bolt or screw-eye or anchor 60 proper, adapted to be disposed in a contiguous part of the riser or tread, preferably in the tread-section, as illustrated in Fig. 1, though in some instances the anchor may be entered directly in the angle formed by the 65 tread and riser, as will be obvious and as illustrated in Fig. 4, it being understood that the eye is designed to be so located that it will register with the opening 4 in the stair-rod. The anchors are spaced apart at a distance equal to the length of the stair-rods, so as to permit the latter to be guided to their seats by the anchors and then fit snugly between them.

In order to constitute a suitable finish, I 75 provide the terminal plate or anchoring member 6, formed of any desired ornamentation or shape, as is common, said anchoring-terminal being designed to carry upon its inner side the tongue or finger 7, said finger being 80 preferably formed of a suitable piece of wire or the like, adapted to extend through a suitable aperture 8, formed in the plate 6 near the central portion thereof, as more clearly shown in Fig. 3, thereby disposing a portion 85 of the wire upon the outside of the plate, usually partly embedded within a suitable groove formed in a contiguous part of the plate, while the extreme outer end of the wire finger is bent under the extreme outer terminal 90 of the plate, as indicated by the numeral 9, said terminal being disposed in close contact with a contiguous part of the plate, thereby insuring that when so clenched or disposed the rod will be very securely held against 95 casual displacement. If preferred, a drop of solder may also be employed upon the terminal 9. It is obvious, however, as will be hereinafter set forth, that said finger may be otherwise secured in place upon the inner side of 100 the plate 6. I also prefer to sharply bend or corrugate a portion of the free end of the finger 7, so as to provide the seat 10, said seat being adapted to engage the anchor 5, and it

is therefore obvious that when the anchoring terminal or plate 6 shall have been forced home upon the end of the stair-rod and the finger entered through the anchor 5 the free 5 end of said finger will be disposed within the aperture 4, and thereby hold the plate in place, the tension of the anchoring-finger 7 being sufficient to insure against casual removal.

10 By reference to Fig. 3 the combination of the stair-rod and combined ornamental and anchoring plate 6 is clearly set forth. In some instances the outer side of the aperture 4 may be cut away, whereby the recess 11 15 will be formed in the end of the stair-rod, said recess being designed for the reception of the hook-terminal 12, having the shank 13 and the inwardly-directed anchoring-terminal 14, as fully illustrated in Fig. 4. The hook-terminal 12 is also provided with the corrugation or seat 15, adapted to receive a contiguous part of the anchor 5, as above set forth. The anchoring-plate 6, provided with the hook-terminal 12, substantially as above described, 20 25 is disposed in operative combination with the stair-rod 3 by placing said hook within the recess 11 and then drawing the plate slightly outward until the anchor 5 shall have dropped within the seat 15, as will be clearly understood.

30 In some instances the anchoring terminal or plate 6 may be provided with a suitable filling 16 of any desired material, said filling or body proper being held in place in any preferred way, as by the flange-sections 17, located at proper points and formed integral with the plate, it being understood, as hereinbefore stated, that said plate may have any desired form or configuration to render it ornamental, attractive, and pleasing to the eye.

40 It will be understood that the body portion proper or filling 16 is designed to occupy only the outer half, more or less, of the ornamental plate, leaving the inner end thereof free 45 to extend over a contiguous point of the stair-rod, whereby the juncture-point of the rod and filling or body proper, 16, will be hidden from view. The filling 16 not only imparts a greater degree of rigidity to the ornamental 50 terminal, but also provides convenient, cheap, and efficient means for anchoring the finger or anchor-engaging section 18, corresponding to the finger 7 in Fig. 3, and having the corrugated portion or seat 19, designed for the 55 purpose hereinbefore set forth. In some instances said anchoring-finger may be bifurcated, as indicated by the numeral 20, each finger having a corrugation or seat 21, adapted to engage a contiguous part of the cross-head 60 22 or that form of anchoring device illustrated in Fig. 6 and other views, it being understood that a pair of apertures 24 are provided in a contiguous part of the end of the stair-rod, said apertures being so located that they will

rest immediately below the cross-head 22 and 65 permit the fingers 20 to pass thereunder, one upon each side of the shank 23, until the cross-head shall rest within the seats 21, it being obvious that the normal resiliency of said fingers will reliably hold the ornamental 70 terminal in place.

While the spring tension of the anchoring-fingers will reliably hold the anchoring plate or terminal 6 to the performance of its office, yet it is obvious that by the application of a 75 proper amount of force said terminal may be moved outward, and thereby disconnected from the stair-rod, permitting the latter to be readily removed and as easily replaced. In the case, however, of the hook-terminal an 80 outward pull upon the anchoring-plate 6 will lock the same all the more securely, inasmuch as an initial inward movement of the plate will be required before the hook will have become disengaged from the anchor. 85

In view of the foregoing description it is obvious that a variety of modified forms of construction may be provided for uniting the stair-rod and its ornamental terminal, and while I have described the preferred combination and construction of parts I desire to comprehend in this application all substantial equivalents and substitutes that may be considered as fairly falling within the scope and purview of my invention. 95

Believing that the construction and manner of using my improved combined ornamental and anchoring terminal for stair-rods have been made clearly apparent from the foregoing specification, considered in connection 100 with the accompanying drawings, further description is deemed unnecessary.

What I claim as new, and desire to secure by Letters Patent, is—

1. The combination of a rod having openings at the ends, plates, each having an inwardly-directed anchoring device formed with seats and located on the inside of the plates, and anchors located one at each end of the rod and receiving the rod wholly between 105 them and adapted to engage the anchoring devices.

2. The combination of a rod having openings at the ends, plates, each having flange-sections, fillings secured within the plates by 115 the flange-sections, inwardly-directed anchoring devices formed with seats and secured to the fillings and anchors located between the rod and the fillings and receiving the rod wholly between them, and adapted to 120 engage the anchoring devices.

In testimony whereof I affix my signature in presence of two witnesses.

ROBERT H. WARREN.
